FLOWER ARRANGER

Robert H. C. M. Daenen, Erembodegem, and Pieter K. J.
De Coster, Aalst, Belgium, assignors to Dart Industries
Inc., Los Angeles, Calif.

Filed July 29, 1974, Ser. No. 492,802

Term of patent 14 years

Int. Cl. D11—02

U.S. Cl. D35—3 R

FIG. 1 is a side elevational view of a flower arranger embodying our ornamental design;

FIG. 2 is a top plan view thereof;

FIG. 3 is a side elevational view of a modified version of the flower arranger shown in FIG. 1; and

FIG. 4 is a bottom plan of the embodiment as shown in FIG. 3.

We claim:

The ornamental design for a flower arranger, substantially as is shown and described.
